THOMAS LOUDEN, OF FAIRFIELD, IOWA.

BUILDING-BLOCK.

1,108,506.

Specification of Letters Patent.

Patented Aug. 25, 1914.

Application filed February 3, 1913. Serial No. 745,822.

To all whom it may concern:

Be it known that I, THOMAS LOUDEN, a citizen of the United States, residing at Fairfield, in the county of Jefferson and State of Iowa, have invented a new and useful Improvement in Building-Blocks, of which the following is a specification.

My invention relates to hollow blocks for building purposes which are made of cement, 10 burned clay or similar material, and it consists of improved means for tying the blocks together, and of other features set forth in the specification and more specifically pointed out in the claims.

15 In the accompanying drawings forming a part of this specification, Figure 1 is a plan view of a portion of a curved wall embodying my invention. Fig. 2 is a vertical section of a portion of said wall drawn longitudinally through the center of the wall, the mortar or cement being left out. Fig. 3 is 20 a perspective of one of the blocks viewed from the top. Fig. 4 is a perspective of one of the tie-plates used to tie the blocks together.

25 Referring to the drawings, the blocks are represented by A and the tie-plates by C. The blocks are shown slightly curved, which is advisable in building curved walls for silos and the like, but for straight walls they 30 may be made entirely straight, and should always be substantially rectangular. The blocks are set in the wall with the openings in a vertical position thus having vertically disposed transverse walls B.

35 In commencing to build the wall a lower tier of blocks is first set on a foundation (not shown in the drawing), with the ends constituting the transverse walls B loosely abutting 40 each other. Another tier of blocks is set upon this tier in the same manner so as to "break joints," as known in the art. As many additional tiers of blocks are then set upon these in the same manner as may be 45 necessary to complete the wall. The tie-plates C used to hold the blocks together are made rectangular and have their central portions depressed and their ends D offset upwardly so as to form shoulders on both 50 sides of the plates, the shoulders on the upper sides facing inwardly and the shoulders on the lower sides facing outwardly. The tie-plates are placed on the lower tier of blocks with their depressed portions in 55 the upper end of the opening of each block, and the offset ends D resting on the upper edges of the transverse walls B. The tie-plates will substantially close the openings in the blocks and the shoulders on the lower sides will approximately abut the upper 60 edges of the transverse walls. In setting the next tier of blocks the lower edges of the transverse walls will rest on or over the depressed portions of the tie-plates and will approximately abut the inner faces of the 65 offset ends D. To close up the spaces between the ends of the blocks the abutting faces of the transverse walls B are plastered with an adhesive material, such as cement or even common mortar, which being abutted 70 together will form a good close solid joint. It is preferable that the abutting faces of these walls be slightly recessed or otherwise arranged to provide more room for the mortar than if made entirely flat thus producing 75 a better joint. In case the mortar plastered on the ends of the blocks does not completely fill the space between the blocks additional mortar may be slushed in the openings between them (shown in Fig. 1) to make a 80 perfect joint. The first tier of blocks being set and their upper edges mortared, the tie-plates are set in position and are plastered over with mortar. The plates are intended to substantially close the openings in the 85 blocks thus forming a solid mortar base the entire width of the block. All openings between the sides of the tie-plates and the side walls of the blocks should not be so wide that the mortar will drop through and leave 90 an opening. In this way the openings in the blocks will be completely closed and be converted into isolated "dead air" spaces instead of flues running from the bottom to the top of the wall, which would be the case 95 if the joints at the tie-plates were not perfectly closed. In case the openings between the abutting walls B should not be sufficiently closed, mortar or cement may be slushed in between the ends D of the next 100 tier of tie plates C, the openings between their ends being specially left for this purpose. The first tier of tie-plates being properly placed, the ends of the second tier of blocks will be mortared the same as the first, 105 and will then be set on the tie-plates as already described. The mortar on the tie-plates will fill the spaces between the lower inner edges of the transverse walls of the last tier of blocks and the inner faces of the 110 tie-plates, and with the mortar between the blocks, will make a solid mortar joint across

the blocks. Additional tiers of tie-plates and blocks will now be set in the manner described until the wall is completed. The arrangement is such that each tie-plate is placed on a single lower block with its depressed center entering the upper edge of the opening therein while the lower adjacent edges of the transverse walls of two upper blocks are placed in the depressed portion of each tie-plate, thus not only securely tying the blocks together, but, with the aid of the mortar used, effectually closing the opening in each block and also by means of the loosely fitting construction, permitting considerable variation in the curve of the wall without having to change the shape of the blocks. If preferred the tie-plates may be made of metal instead of a clay product.

By the construction and arrangement herein described, it will be seen that the blocks cannot be drawn apart as long as the tie-plates and transverse walls of the blocks remain intact. Neither can one tier of blocks be drawn endwise or in anyway out of line on another. The arrangement of the tie-plates makes a good wide, close, durable mortar joint between every tier of blocks having single openings, and at every other tier when blocks with three openings are used. Also, the transverse end walls B being mortared all over will form durable mortar joints between each of the blocks thus insuring good solid mortar joints all around the blocks the full thickness of the wall, and at the same time forming an isolated "dead air" space in each and every block.

When blocks having horizontally disposed openings are used there is always trouble in getting the ends of the blocks sufficiently mortared to make a good durable joint. The abutting ends of the blocks with horizontally disposed openings are seldom over three-quarters of an inch thick, and sometimes not over half an inch thick and when used for building silos, the silage acid on the inside and the freezing and thawing on the outside will in time cut through these thin joints of mortar and make openings in the wall which will spoil the silage or render a building cold. By my invention this defect is overcome and a strong durable wall is produced having large isolated "dead air spaces" throughout which will effectually keep out frost and cold in any ordinary climate. The tie-plates will hold the blocks together at both top and bottom instead of one side only. When clips are used which catch over the upper edges only, the blocks will not be held together at both sides. The ties are also economical in holding the mortar and preventing it from dropping into the openings and being wasted. In case the ties should be a little too narrow to effectually close the openings, a strip of metal lath

may be laid on the open side or other means may be used to catch and hold the mortar and form a solid mortar joint.

The entire arrangement is extremely simple and easily laid, and is effective in every respect both in holding the blocks securely together and in forming isolated "dead air" spaces throughout the wall. Also the construction is such that ordinary variations in the size and shape of the blocks and ties, caused by shrinkage and warping in burning is amply provided for, which cannot be successfully done when the ties have notches in both their upper and lower faces. Furthermore, the tie-plates may be made of uniform thickness, which is an important feature that cannot be had when there are notches in their faces and they do not have to be made wider on their outer than on their inner sides when used in a curved wall.

What I claim is:

1. In a wall, the combination of a series of hollow building blocks placed in a row, each having a vertically disposed opening and transverse walls, a series of tie-plates, each having a depressed center corresponding approximately to and entering the upper edge of the opening in the block below it and having upwardly offset ends resting on the transverse walls of the block, and another series of hollow blocks similar to the first laid upon the first series so as to break joints, and the lower edges of the adjacent transverse walls of said blocks inserted in the depressed portion between the upwardly offset ends of the tie-plate immediately below said transverse walls.

2. In a hollow wall, the combination of a series of superposed blocks having vertical openings and abutting transverse walls, a series of tie-plates each having a depressed center, corresponding to and entering the upper edge of the opening in a block, and upwardly offset ends resting upon the transverse walls of the block, the upwardly offset ends of the adjoining tie-plates being bound together by entering the lower edge of the vertical openings of the blocks above and being held by the transverse walls of said blocks.

3. In a wall, a plurality of superposed series of hollow building blocks, open at their upper and lower ends and having transverse walls, in combination with a plurality of series of interposed tie-plates, each provided with a depressed portion and upwardly offset ends, the said depressed portion corresponding to and entering the opening in the upper end of an adjacent block, the upwardly offset ends resting upon the transverse walls thereof, and the lower edges of the transverse walls fitting loosely in the depressed portions of the tie-plates in the next lower series of blocks and plates.

4. A plurality of superposed series of hol-

low building blocks, having vertical openings and abutting transverse walls, in combination with a plurality of series of interposed tie-plates each provided with a depressed portion and upwardly offset ends, the depressed portions of the tie-plates corresponding to and entering the openings in the blocks below, the upwardly offset ends resting upon the transverse walls thereof,

and the lower edges of the adjacent transverse walls of the blocks fitting loosely in the depressed portions of the tie-plates in the next lower series.

Fairfield, Iowa, Jan. 30, 1913.

THOMAS LOUDEN.
